UNITED STATES PATENT OFFICE.

JAMES F. CRAVEN, OF PITTSBURGH, PENNSYLVANIA.

GREASE-CUP.

1,351,841.

Specification of Letters Patent.

Patented Sept. 7, 1920.

Application filed March 31, 1917. Serial No. 158,895.

To all whom it may concern:

Be it known that I, JAMES F. CRAVEN, a resident of Pittsburgh, in the county of Allegheny and State of Pennsylvania, have 5 invented a new and useful Improvement in Grease-Cups, of which the following is a specification.

This invention relates to automatic grease cups to be used for feeding a lubricant into 10 machine bearings. More particularly it relates to a device of the class stated for automatically feeding the lubricant at a constant rate, and to means for controlling the rate of feed by an adjustable air valve.

15 It is intended to provide a grease cup of a comparatively simple form, which may be readily filled and refilled, in which the rate of feed of the lubricant may be adjusted to an extreme degree of exactness, 20 and this rate of feed maintained throughout the emptying of the cup, and in which lubricants of varying degrees of viscosity, from very thick grease to light oil, may be fed without change of cups, or parts. Another 25 object is to provide a grease cup having in effect a safety reservoir, retaining a small amount of lubricant, which will be fed to the bearing after the normal discharge of the cup has ceased, upon the heating of the 30 bearing by reason of friction resulting from the cessation of flow of the lubricating medium.

Other objects and advantages will more fully appear throughout the following specification.

35 Referring to the drawings, Figure 1 is a central vertical section through the completely assembled cup, showing the lubricant expelling follower in withdrawn position, 40 as when the cup is full; Fig. 2 is a similar view showing the parts in relative position after the contents of the cup have been discharged; and Fig. 3 is an enlarged partial section showing details of the air valve for 45 controlling the rate of feed of the cup.

For the lubrication of machine bearings, 50 which are in more or less constant use, and particularly for bearings which are themselves on moving parts and therefore not readily accessible to the operator in charge of the machinery, receptacles for lubricants have been provided, the lubricants being retained in a chamber under pressure sufficient to force them into the bearings, and 55 springs provided to exert pressure on the contents of the cup to insure a more or less

constant feed. Various devices have been employed for insuring that this feed be certain, and constant throughout the travel of the expelling follower. Such means have, however, always been positive mechanical devices of one form or another, usually a variation in the spring of the driving spring itself, of the form of follower, or of the cup wall. The rate of feed- 60 65 with such devices has depended somewhat on the consistency of the lubricant, and it has not been possible to use oil in devices of the character referred to.

The present invention avoids these and 70 other disadvantages and difficulties, by providing an air-tight grease cup which will automatically feed to the bearing to be lubricated, the rate of feed being entirely controlled by the passage of air into the cup 75 through a valve which has a micrometer control. The lubricant can be expelled from the cup only so fast as air passes through the valve, and therefore the rate of feed is less dependent upon the force of 80 the driving spring than in the prior devices, and is completely regulable in that the amount fed can be entirely controlled as to the maximum amount of lubricant expelled in any given period. By the particular con- 85 trolling means of this invention it is possible to use lubricants varying in consistency from a very thick pasty grease to a light oil, and to secure a regular and even flow of lubricant, from exactly similar cups, one 90 of them containing heavy grease, the other a light oil.

Referring to the drawings, the grease cup comprises a casing 1, having exterior threads 95 at its lower end engaging similar threads in a base member 2, which has a taper bored portion 3, and central outlet 4, through a threaded extension 5, which is adapted to be screwed into the bearing to be lubricated. Between this threaded portion 5 and the 100 tapered portion 3 is provided a shoulder 6, which is either square, hexagonal, or of other suitable shape to be gripped by a wrench for securely fastening into the bearing.

The casing 1 has a cylindrical bore 7 forming the main lubricant containing chamber, which is open at the bottom to the outlet through the base member 2. The upper end is closed by a wall 8, which has a 110 central bore extending therethrough, this bore being surrounded by an exterior bush-

ing 9, and a bushing 10 extending for a considerable distance inside the chamber 7, the bore being continuous through the two projections and casing wall. Through this bore 5 in the top of the casing a stem 11 operates. The bore and stem are carefully machined so as to form a close, accurate fit, not varying more than a few ten thousandths of an inch, at the most. The upper end of the stem 11 has threads 12 thereon, and the lower end 10 has a plurality of annular grooves 13 extending around it. These grooves are of such number and so placed and spaced on the stem that the uppermost one never passes 15 out of the bore of the bushing 10 in the extreme downward travel of the stem, for purposes more fully explained hereinafter. The stem has a central bore 14, at its upper end, a smaller central bore 15 continuing 20 from the larger bore and extending nearly to the lower end of the stem, and connecting with that portion of the chamber 7 behind the follower, below described, which portion of the chamber is designated 7^a. 25 The lower end of the stem is riveted over and rigidly carries a sheet metal member which is pressed to form a follower 17, extending across the chamber 7, and making a close fit with the wall thereof by means of a 30 flexible washer member 18, carried by a flange 19, at the outer edge of said follower, as will be apparent from an inspection of the drawings, and as is usual in such construction. The follower is formed with a 35 reentrant portion comprising an inner wall 20, an outer wall 21, and a connecting portion 22, the flange 19 being turned over from the edge of the wall 21. A coiled spring 23 surrounds the follower in the space 40 between the wall 21 and the casing, having one end bearing against the end wall 8 of the casing, and the other end clamping the washer 18 against the flange 19 of the follower. It will be noted that the inner wall 45 20 of the follower has a clearance space between it and the outside of the bushing 10, so that the air can pass freely from the passage 16 into the space 7^a behind said follower. 50 The larger bore 14 of the stem 11 is made with a bit having a tapered point, so that there is a beveled shoulder 24 at the junction of the larger bore 14 and the smaller bore 15. A knurled nut 25 engages the outer threads 55 of the stem 11, and is adapted to withdraw said stem, and the attached follower upon being turned down on the stem in abutment with the projection 9 of the upper casing wall. 60 Working in the larger bore 15 of the hollow stem is a valve member comprising a threaded portion 26, coöperating with interior threads in the bore 14, and having an exterior screw head 27. Below the threaded 65 portion 26 the valve member is turned down

to form a portion 28 of smaller diameter allowing a surrounding space, and near its lower end the valve member is still further reduced, forming a shoulder 29, and a portion 30, adapted to extend into the smaller bore 15 of the stem. This portion 30 of the valve member is very slightly tapered from the shoulder 29 to its end, so that a considerable travel of the valve member occurs for slight variation in the area of passage 75 around this closure valve and the wall of bore 15.

By this construction the travel downward of the valve member gradually closes the bore 15, and the change in opening because 80 of the tapered valve, is so very gradual as to allow an exceedingly fine adjustment in the passage. The tapered valve will contact with the wall of the bore 15 only at the junction point of the two bores, and the 85 first time the valve is forced into position the contact point on the outer wall will be formed into an effective valve seat, and thereafter there will be very little wear of the parts. A locking nut 31 engaging the 90 threaded portion 26 of the valve member is provided, by which the valve may be securely fastened in any desired position of adjustment. It will be understood that the threaded engagement of the valve member 95 and the interior of the follower stem is loose, as also the engagement of the locking nut 31 with the valve member, so that air will readily pass through the opening formed by the threads, and the control of the passage 100 of air to the inside of the cup will depend entirely upon the relative position of the tapered valve portion 30 in the smaller bore 15 of the follower stem.

The operation of the device is as follows:—

By removing the casing 1 from the base 2, and withdrawing the follower 17 to the position shown in Fig. 1, the cup may be filled with the lubricant which is to be fed 110 therefrom. Then the casing is securely threaded into its base, and the nut 25 turned back on the stem 11 to its uppermost position, as shown in Fig. 2, thus allowing the full force of the coiled spring 17 to bear 115 against the follower to expel the grease from the cup into the bearing to be lubricated. However, the follower, when the cup is filled with grease, makes an air-tight fit in the casing and the travel downward of the follower tends to create a vacuum in the space 120 behind it, in the casing. This partial vacuum can only be relieved by passage of air into the exhausted space through the bores 14 and 15, which are controlled by the tapered valve 30. By experiment the valve is adjusted to exactly the right point to permit passage of air to the exhausted space, and consequently to permit the follower to 125 expel the grease from the cup, at the rate 130

of feed desired. The coiled spring is chosen of such strength that it will exert a strong force throughout the entire travel of the follower, and will not be appreciably weakened as that member approaches the limit of its expelling motion. This renders the rate of travel of the follower in expelling the grease dependent exclusively on the rate at which air is supplied to the space behind it, and this is absolutely controlled by the adjustment of the valve member 30.

Since the rate of movement of the follower is dependent upon the supply of air to the space therebehind, it is evident that lubricants of varying degrees of viscosity may be used in the same cup, and that they will be supplied regularly at a predetermined rate of feed.

The annular grooves 13 around the lower end of the follower stem are filled with oil before the stem is inserted through the guiding bushing, and these grooves, with the close fit of the stem and its guiding bearing, are sufficient to prevent the passage of any air into the space 7^a around the stem 11. The oil in the grooves 13, because of its capillary attraction, and resistance to distribution, acts as a packing, the efficiency seeming to increase with the amount of air pressure that is exerted thereon. This packing is important not only as preventing the passage of air into the cup, but also as allowing some variation in the machining of the stem and its guiding bore. The amount of allowable variation makes quantity production by machining possible. It will be observed that these grooves are of such number and so situated that always at least one of them is inside the bushing 20, as shown in Fig. 2. It will also be observed that at the time when the smallest number of these packing grooves is in operation to prevent passage of air around the follower stem, the spring is then at its weakest point, so that as the packing element becomes less resistant the spring creating the exhaust tending to force air through the packing is also weakened in direct proportion, and the efficiency of the joint is consequently maintained throughout the entire travel of the follower in the casing.

The form into which the metal follower is pressed, besides providing for the least practicable space behind the follower, provides an annular open recess therein, which will retain a certain amount of the lubricant, which cannot be expelled by travel of the follower to its lower limit. Should the cup not be refilled at the end of its expelling action, the grease retained in the recess referred to will act as a safety reservoir or additional supply, which will only be fed to the bearing in case the latter becomes heated upon the failure of the lubricant normally supplied thereto. In this latter

case, the reserve will furnish a safeguard, preventing material injury to the bearing during a considerable space of time in which the operator will have occasion to observe that the cup has been emptied, and know 70 that it should be refilled.

I claim:—

1. An automatic grease cup comprising an air-tight lubricant retaining casing, a driven follower therein making air-tight engagement therewith, a passage to admit air behind the follower, and a valve to regulate the rate at which air is admitted through said passage. 75

2. An automatic grease cup comprising a 80 casing, a driven follower therein, a stem on the follower extending through a passage in the end of the casing, an air passage through the stem to the interior of the casing behind the follower, and an adjustable valve controlling said air passage. 85

3. A grease cup comprising a casing, a driven follower therein, a stem on the follower extending through a passage in the end of the casing and having a lubricant 90 packed fit therein, an air passage through the stem to the interior of the casing behind the follower, and a valve controlling said air passage. 90

4. A grease cup comprising a lubricant-95 retaining casing, a follower therein making air-tight engagement therewith, a spring behind the follower, a passage through the casing behind the follower, an adjustable valve controlling the passage, and means to lock 100 the valve in adjusted position.

5. A grease cup comprising a lubricant-retaining casing, a follower therein making air-tight engagement therewith, means to drive the follower through the cup, an air 105 passage through the casing behind the follower, an adjustable valve controlling said passage, and means to lock the valve in adjusted position.

6. An automatic grease cup comprising a 110 casing, a follower therein adapted to expel grease therefrom, a stem on the follower extending through a wall of the casing and having an air-tight fit therewith, an air passage through the stem to the interior of 115 the casing behind the follower, a valve controlling said air passage, and exterior means engaging said stem to withdraw the follower against the driving means.

7. An automatic grease cup comprising a 120 casing, a driven follower therein, a stem on said follower extending through a wall of the casing and threaded on its outer end, a nut engaging said threaded stem and abutting the casing to withdraw the follower 125 against the pressure of the driving means, an air passage through the stem to the interior of the casing behind the follower, and a valve controlling said air passage.

8. An automatic grease cup comprising an 130

air-tight lubricant-retaining casing, a driven follower therein adapted to expel grease therefrom, an air passage into the casing behind the follower, means for controlling said passage comprising a tapered valve adapted to fit into the passage, means to adjust the valve, and means to lock the valve in adjusted position.

9. An automatic grease cup comprising an air-tight lubricant-retaining casing, a driven follower adapted to expel the contents of the cup, an air passage leading into the casing behind the follower, a threaded valve member controlling said passage by means of a tapered end thereon, and a locking nut for retaining the valve in adjusted position.

10. A grease cup comprising a base member adapted to screw into a bearing to be lubricated, a casing open at one end and adapted at the open end to screw into the base member, a driven follower in the casing adapted to expel a lubricant from the cup, a stem on the follower extending through a passage in the end of the casing, an air passage through the stem to the interior of the casing behind the follower, an adjustable valve member controlling said air passage, and means to lock the valve in adjusted position.

11. An automatic grease cup comprising a base member adapted to screw into a bearing to be lubricated, a casing adapted to screw into the base member and form a grease cup, a follower in the cup, a spring to drive the follower to expel the contents of the cup, a stem fixed on the follower and extending through a wall of the cup and making an air-tight fit therewith, an air passage through the stem, a valve controlling said air passage, means to adjust the valve and to lock it into adjusted position, and exterior means to withdraw the follower against pressure of the driving spring.

12. An automatic grease cup comprising a base member adapted to screw into the bearing to be lubricated, a cup-shaped casing adapted to be screwed into the base member, and a driven follower adapted to expel the contents of the cup through the base member, said follower being formed with a reentrant annular recess therein adapted to retain a reserve supply of lubricant after the follower has reached the limit of its expelling movement.

13. An automatic grease cup comprising a casing having a driven follower therein adapted to expel the contents of the cup and to make air-tight engagement with the wall thereof, a stem fixed on the follower and extending through a bore in the casing wall and making an air-tight fit therewith, a central bore in the stem, a smaller central bore extending beyond the first named bore and having an opening extending to the interior of the casing behind the follower, a threaded valve member in the larger bore of the stem having a tapered end adapted to extend into the smaller bore and to seat on the shoulder formed by the junction of the two bores in the stem, and means to lock the valve member in position.

14. In an automatic grease cup comprising a casing, a driven follower therein making air-tight engagement therewith, and a stem on the follower extending through the casing wall, the combination of a guiding bore for the stem, and annular grooves on the stem adapted to be filled with oil to make an air-tight packing between the stem and its guiding bore.

15. In an automatic grease cup comprising an air-tight casing having a driven follower therein adapted to expel the contents, the combination of a cylindrical stem fixed on the follower, a guiding bore through the casing for said stem, and annular grooves on the stem adapted to retain a semi-liquid packing element to prevent passage of air through said bore around said stem.

16. In an automatic grease cup comprising an air-tight casing having a follower therein and means to drive the follower to expel the contents of the cup, the combination of a stem fixed on the follower having a central bore therethrough to admit air to the casing behind the follower, and a valve controlling said passage, the combination of a guiding bore through the casing for the follower stem, and annular oil-retaining grooves on the stem adapted in coöperation with the guiding bore therefor to prevent the passage of air around the stem into the casing.

In testimony whereof I have hereunto set my hand.

JAMES F. CRAVEN.
